AUTOMATIC HEAT MACHINE

Allen J. Johnson, Delaware County, Pa., assignor,
by mesne assignments, to Anthracite Heat Ap-
pliance Corporation, Dover, Del., a corporation
of Delaware

Application December 29, 1933, Serial No. 704,486

1 Claim. (Cl. 110—45)

This invention relates in general to heating devices and more particularly to an automatic furnace which will be suitable for supplying heat in the form of steam, hot water, or other hot liquid, 5 through a heating plant.

One of the objects of this invention is to provide a completely automatic heating machine which will automatically convey coal from the bin and convey the ashes to a remote point, and 10 to arrange such conveying devices so that the conveying of the coal and the removal of the ashes will be operations which may be independent of each other.

Another object is to provide a heating device 15 which will consist of very few moving parts which will be fully enclosed and provided with the minimum adjustments or necessity for same.

Another object is to provide an improved and efficient system of zoning the air so as to permit 20 a fine adjustment of the fuel to the conditions present so as to insure an efficient combustion.

With the foregoing and other objects in view, the invention consists in the combination of parts and in the details of construction hereinafter 25 set forth in the following specification and appended claim, certain embodiments thereof being illustrated in the accompanying drawings, in which:

Figure 1 is a view in cross-section taken through 30 the lower portion of the heating device showing the tuyère pot in section;

Figure 2 is a view in section taken along line 2—2 of Figure 1;

Figure 3 is a view in section taken along line 35 3—3 of Figure 1;

Figure 4 is a view in section taken along line 4—4 of Figure 3;

Figure 5 is a view in section taken along line 5—5 of Figure 3;

Figure 6 is a diagrammatical showing of the 40 coal and ash conveyor;

Figure 7 is an enlarged sectional detail view of the ash conveyor shown in Figure 3.

Referring more particularly to the drawings, 45 the heating device consists in a main outer casing 1 with an inner wall 2 between which walls there may be provided suitable heating insulation material 3. The coal, or other fuel, is conveyed through an aperture 4 into a conveyor 5, which 50 is provided with a spiral screw 6 which, when rotated carries a certain amount of coal into a position for combustion immediately below the tuyère pot 7. This fuel conveying spiral member 6 is carried by a shaft 8 which in turn carries a ratchet wheel 9. As the shaft 10, driven by a

suitable electrical motor 11, is operated, rotary motion is imparted to a crank 12 and thence to a crank 13 so as to intermittently bring a pawl 14 into engagement with ratchet wheel 9 so as to impart the necessary and predetermined rotary motion to the shaft 8. Such a rotary motion to shaft 8 will cause a certain number of turns of the spiral conveying member and thus bring a predetermined amount of fresh fuel supply into position below the tuyère pot for combustion purposes. 10 The link 13 is pivotally connected at 55 to a link 56 carried loosely by shaft 8 so as to allow for necessary flexibility of operation.

The spiral conveying screw 6 is preferably formed with a reverse screw portion 6' so that if 15 there is any tendency for the fuel to be carried past the central lower opening 7' of the tuyère pot, the reverse threads return and refeed such fuel as well as such fuel or siftings which may have dropped down from the tuyère pot back to 20 the furnace in the proper position below the tuyère pot.

The motor 11 also drives a blower 16 through the medium of a shaft 17. As shown in Figure 4, a passageway 18 is provided in the casing for the 25 air forced through it by the blower. This passageway as it nears the tuyère pot is subdivided into three passageways 18a, 18b and 18c, which communicate respectively with compartments 7a, 7b and 7c, circularly and concentrically arranged 30 with respect to the tuyère pot. The tuyère pot is provided with a large number of apertures 19 throughout its funnel-shaped sidewalls, there being a number of such apertures in the sidewalls adjacent each of the compartments 7a, 7b and 7c. 35 This is for the purpose of aiding the combustion and the intensity thereof. Any suitable regulating means may be employed for selectively opening or closing one or more of the subdivisions 18a, 18b or 18c. 40

The fuel has been stated as being fed in through the aperture 4 into the screw conveyor housing 5. In order to remove the source of supply, however, there is provided a device whereby the fuel may be brought from a remote point in a series of rings 45 attached to a cable and by the use of the same device the burned ashes may be removed from the furnace and dumped at a point remote. In order to make this possible, there may be provided a circular idler frame 20 rotatably mounted about the tuyère pot on the rollers 15. This frame carries at spaced intervals about its periphery a series of projections 21. An endless belt, cable or chain 22 is fitted about the frame 20 so as to be engaged by a plurality of projections 21. This 50 55

belt, cable or chain is carried to a point remote from the furnace where it is stretched about a drum 27 driven independently of the motor 16 and the screw 6. The tuyère pot remains stationary but the remotely driven cable and rings by engaging the projections 21 of the idler frame 20 rotates the latter. The projections 21 in their rotation with the frame 20 act as scrapers for scraping the ashes in the ash pit as they fall over the top of the stationary tuyère pot. The scrapers 21 scrape the ashes from the point of exit of the rings 30 into the extension 25 to the point of entrance of the rings into the ash pit from the extension 26 at which point the rings by reason of their relative size as compared to the scrapers 21 perform the function of carrying the ashes around the greater portion of the ash pit and thence out through the pipe 25 to a remote ash receiver 24' into which the ashes are dumped. The tuyère pot casting is extended at 25 and 26 to receive pipes 28 and 29. The endless belt, cable or chain 22 may carry a series of rings 30 for collecting fuel from a remote coal feeding station 24 and bringing it in through pipe 29 from which it is dumped out through the hole 29' into the funnel 4 of pipe 5 containing the coal feed worm 6. The rings 30 as they continue their travel pick up the ashes about the tuyère pot and carry them out of the furnace through pipe 28 in which there may be a discharge opening similar to 29' at a remote point for dumping the ashes into the ash receiver 24'. The worm 6 if desired may be extended past the end of pipe 5 directly into a remote coal feeding station 24, and instead of having the cable 22 and rings 30 handle both the coal and ash in which case the worm will bring the coal in direct from the coal feeding station and the cable and rings will remove the ash. The travel of the rings continues from the

point at which the ashes are dumped into the remote ash receiver 24' until it engages coal fed into the pipe which it carries forward to be dumped into the funnel 4.

The motor, as previously described, is adapted to intermittently drive the shaft 8 and this is brought about in such a manner that upon each revolution of the motor shaft 10 the pawl 14 advances the ratchet wheel 9 the distance of one tooth, causing an oscillation of shaft 8 throughout a corresponding arc of movement, as shown in Figure 5.

I claim:

In combination with a furnace for burning solid fuel, a stationary tuyère pot, a stoker including a conduit with an inlet exterior of the furnace, an outlet adjacent said pot and a motor driven stoking mechanism within said conduit for feeding said fuel from said inlet to said pot, an ash pit arranged circumferentially of said pot and a ring rotatably mounted in said ash pit to collect the ash as it falls over the sides of said pot, said ring having circumferentially spaced projections thereon, a motor driven endless belt extending partially about the circumference of said ring, inlet and outlet conduits for enclosing said endless belt, said belt being provided with spaced members for engaging the projections on said ring to rotate the latter and to force the accumulated ash into the outlet conduit and through an outlet therein to a remote point for dumping, said belt and its spaced members being adapted on their return movement to feed fuel let in at a remote point into the inlet conduit and out thereof into the inlet of the conduit enclosing said stoking mechanism, said endless belt and said stoking mechanism being driven independently of each other.

ALLEN J. JOHNSON.
